UNITED STATES PATENT OFFICE

THEODORE F. VON DORN, OF NEW YORK, N. Y.

TWO-PIECE RAILWAY RAIL ANCHOR

Application filed December 18, 1930. Serial No. 503,302.

This invention pertains to new and novel improvements in rail anchors formed from two pieces of high grade spring steel especially designed to be fixedly secured to the base portion of a railway track rail, and in engagement with stationary parts of the railway road bed for the purpose of preventing longitudinal displacement of the track rails during the travel of the rolling stock 10 thereover.

The prime object of the invention is to provide a simple, novel, durable, practical, economical and thoroughly efficient rail anchor of the desired and required dimensions 15 possessing the requisite strength, which may be readily applied to the base portion of a track rail and securely maintained in its proper operative position thereon, and which will always effectively grip and clamp the rail base and cooperate with a stationary part 20 of the railway road bed to prevent any creeping action of the track rail.

Another object of the invention is to so construct my improved two piece rail anchoring 25 device that it will always maintain the required resiliency and tension and exert an extremely tight gripping, clamping and effective frictional engagement with the track rail under any and all conditions of service, 30 and the greater the twisting strain to which the anchor may be subjected the more intense gripping power is imparted thereto.

The foregoing and such other objects as may appear from the ensuing description are 35 accomplished by the construction, formation, location and combination of the several parts hereinafter more fully described, illustrated by the accompanying drawings, and particularly pointed out in the claims appended 40 hereto, it being understood that slight changes in the precise form, proportions and minor details of the construction may be resorted to without departing from the spirit or sacrificing any of the advantages of the 45 invention.

In the accompanying drawings forming a part of the specification it will be seen that:

Figure 1 is a side elevation of the improved device embodying my invention showing the 50 relation that the parts are caused to assume

with respect to the track rail when the said parts shall have been properly applied to said rail, showing the track rail in cross-section, and a cross-tie broken away.

Figure 2 is a plan showing a portion of the 55 track rail broken away and partly in section with a portion of a cross-tie broken away.

Figure 3 is a similar plan showing the position assumed by the locking clip or key when first passed through the opening formed 60 through one end portion of the main anchor member.

Figure 4 is a perspective of the main anchor member detached from the track rail.

Figure 5 is an inverted plan of the member 65 shown in Fig. 4.

Figure 6 is a side elevation of the securing clip or key detached from the track rail and main anchor member, and

Figure 7 is an inner end elevation of the 70 clip or key as shown in Fig. 6.

In the embodiment of the invention as illustrated it will be seen that the numeral 1 indicates a railway track rail, and 2 an underlying cross-tie forming a stationary part 75 of the railway road bed and supporting the rail 1, the said rail having a tendency to creep or move longitudinally, when subjected to the intense strain caused by the travel of the rolling stock thereover.

The letter A designates the main anchoring member which may be formed from any suitable or desirable metal, but is preferably formed from a single bar of high grade steel of the required dimensions, the operation of 85 forming the said member being performed by drop forging or stamping the bar with a downwardly extended or depending U-shaped centrally disposed portion 3, having a flattened portion 4 extending from each side of the upper end of said portion 3, the upper face of each flattened portion 4 being adapted to contact with the lower face of the track rail, while one end portion of the member is suitably bent upwardly and inwardly to form the upper portion of the jaw member 5 that is adapted to overlap and tightly clamp against the upper inclined face of the base portion of said track rail, and the other end portion of said member 100

is provided with an opening 6 therethrough, preferably of a substantially oblong contour, said opening being so formed as to spread the surrounding metal, thereby producing an enlargement 7 at that end portion of the member to assure additional strength thereto, while at the same end portion of this member in its lower face is formed a depression or recess 8 for the purpose herein-after described.

The letter B designates the fastening clip or key formed with a somewhat bow-shaped central body portion having two outwardly extended portions 9 and 9' inclined inwardly from each outer end to its inner end, said body portion being flattened at each side portion 10 thereof, while its inner and outer faces are rounded at 11, the diameter of the said clip or key being greatest at the center of the body portion at the point 12. The extension 9 is formed with a flat inner surface portion 13 adapted to contact with the upper inclined surface of the track rail base and its outer surface is rounded, while the extension 9' is formed with a rounded inner surface portion 14 adapted to be seated in the depression or recess 8 formed in the lower face of member A, and the outer surface is flattened and merges into the rounded surface of the said clip or key.

In the application of the anchoring device to a track rail the member A is first applied to the rail by hand with the jaw member at one end resting on the upper surface of the inclined base portion of the rail at the outer edge of the said base portion, and said member is then forced on the base by striking the member at the point 15 with a suitable sledge or maul thus causing the overhanging jaw member to be forced up the inclined face of the base under extreme clamping tension until the opening formed through its other end is caused to be so disposed that the inner wall of said opening will rest beneath the rail base, at a point adjacent to the outer edge of the rail base, as shown by the dotted lines, Figure 3, with the flattened upper faces of the body portion 4 of said member in close contact with the lower face of the rail base, the clip or key B is then passed by hand through the said opening and caused to assume the position shown in Figure 3, the said clip or key is then turned slightly by hand until its outer extended end portions 9 and 9' are caused to rest in the position shown by the dotted lines Fig. 2 with its upper extension 9 resting near the edge of the rail base and upon its upper inclined surface, when by striking the outer face of the extension 9 with a suitable sledge or maul the extension 9 is forced up the said inclined surface until it is caused to assume the position shown in Figs. 1 and 2, said operation causing the lower extension 9' to simultaneously swing and rise beneath the rail base, until it is caused to assume a position in verti-

cal alinement with the upper extension 9, with the inner rounded face of the extension 9 resting within the depression or recess 8 formed in the member A thereby securely retaining the clip or key in its locked position, and at the same time the said clip or key is being driven or forced into the locked position the rounded outer surface of the body portion of the key being in contact with the outer wall of the opening in the member A, as the clip or key is forced into its horizontal position with relation to said member A, the outer portion of the member A is being forced outwardly until the inner wall of the opening is moved under tension of the downwardly extended body portion until said inner wall is in vertical alinement with the outer edge of the rail base with the outer central rounded surface of the body portion of the clip or key in intense contact with the outer wall of said opening thus maintaining the member A under strong tension in contact with the rail and said tension also preventing any rearward movement of the clip or key and at the same time serving to retain said clip or key in a secure and locked condition.

It will be perceived that the clip or key is of a specially and peculiarly designed formation adapted to securely clamp and intensely lock the member A in contact with the rail base under extreme tension, and at the same time, when said clip or key shall have been forced into its operative position will maintain itself as well as the member A in intense contact with the track rail base.

It will be evident that both members of my improved rail anchoring device may be formed of any suitable or desirable metal, and of such dimensions with relation to each other as will most successfully and best serve the purpose for which they are intended.

It will be seen that the open end portions 9 and 9' of the clip or key B are so disposed, with relation to the body portion thereof, that when it is driven into its final locked position, said portions 9 and 9' will be under extreme high tension, while the outer rounded face of said key at the point 12 will be in intense contact with the outer wall of the opening 6 in member A and the inner central rounded face of said key will be away from contact with the inner wall of said opening 6 as shown in Fig. 1 of the drawings.

Having thus described my invention, what I claim and desire to secure by Letters Patent is:—

1. A railway rail anchor comprising two members, one of said members being formed from a plate of high grade spring steel having a downwardly extended central portion with an overhanging jaw member at one end portion and an opening formed therethrough at its other end portion, and a fastening clip adapted to be inserted through said opening and to intensely clamp the upper surface of

the rail base and the lower face of said member, the said member being under extreme tension at all times when in its secured condition.

5 2. A railway rail anchor comprising two members, one of said members being formed from a plate of suitable metal having a depending resilient central portion with an overlapping jaw formed at one end and an oblong opening formed therethrough at its opposite end portion, and a fastening clip passed through said opening and driven upon the inclined upper face of the base of said rail with the upper and lower portions of said 10 clip under high tension and locked in contact with the rail base and said member respectively.

15 3. A two-piece railway rail anchor comprising a member formed from a suitable plate of metal having a depending central portion and an overlapping jaw at one end and an oblong opening formed therethrough at its other end portion, a fastening clip passed through said opening adapted to 20 clamp the upper face of the rail and the lower face of said member, said clip being flattened at each side of its body portion with its upper extension flattened on its inner face and its lower extension rounded on its inner face.

25 4. A two-piece rail anchor of the character described, comprising a member formed with a central depending portion and an overlapping jaw at one end thereof and an oblong hole formed therethrough at its outer end 30 portion and a fastening clip adapted to be passed through said opening, said clip being so constructed that when applied in its locked position it will be under high tension and at the same time maintain said member under 35 high locking tension.

40 5. A railway rail anchor of the character described comprising a member formed with a central depending portion having an overlapping jaw formed at one end and an opening formed through its opposite end portion, a fastening clip passed through said opening, said clip and opening being so formed 45 with relation to each other that when the clip shall have been forced into its locking position both the said clip and the member will 50 be maintained under high locking tension.

THEODORE F. von DORN.
